UNITED STATES PATENT OFFICE.

FREDERICK EDWARD HEINIG, OF LOUISVILLE, KENTUCKY, ASSIGNOR OF
TWO-THIRDS TO CURRAN POPE AND ALFRED THRUSTON POPE, OF
LOUISVILLE, KENTUCKY.

SHEET-METAL FASTENING-CLEAT.

SPECIFICATION forming part of Letters Patent No. 701,267, dated May 27, 1902.

Application filed August 23, 1901. Serial No. 73,067. (No model.)

To all whom it may concern:

Be it known that I, FREDERICK EDWARD HEINIG, residing at Louisville, in the county of Jefferson and State of Kentucky, have invented certain new and useful Improvements 5 in Sheet-Metal Fastening-Cleats, of which the following is a specification, reference being had therein to the accompanying drawings.

This invention relates to sheet-metal holding-cleats for strengthening and securing the heads of barrels, boxes, and like articles.

The object of the invention is to produce a cleat or fastener from sheet metal which when properly applied to the head, chimes, and hoop 15 of a barrel or to the cover and sides of a box will greatly increase the security of the package and which can be quickly applied and removed by a suitable tool without leaving corners or projections, as when nails are used 20 for like purpose.

Figure 1 is a plan of a strip of sheet metal, showing by dotted lines the cuts necessary to make a number of holding-cleats therefrom. Fig. 2 is a plan of the blank as cut from the 25 sheet before bending. Fig. 3 is a plan or elevation of the device ready for application. Fig. 3^a is a plan looking from the holding edge of the fastener or cleat. Fig. 3^b is an end view. Fig. 4 is a perspective of a broken 30 part of a barrel, showing cleat attached. Fig. 5 is a section of these parts. Fig. 6 is a modification showing cleat with holes for holding 35 nails. Figs. 7 and 8 are other modifications.

A strip of sheet metal, preferably sheet- 35 steel galvanized, can be cut into cleats and bent to form by a single operation or otherwise. Preferably the blanks A are cut from the strip in such form that there is no waste of material save at the extremes of the rec- 40 tangular strip. A notch B in the blank is left when the tongue C is cut from the strip. This tongue C is slightly bent, as in Figs. 3, 3^a, 3^b. Points D D are struck from the metal and bent so as to project from the back of the 45 cleat.

In Fig. 6 the cleat is shown with additional means for attachment, such being shown by holes K K.

In Fig. 7 the points D' are struck from the 50 edge rather than from the body of the cleat.

Fig. 8 shows how the body of the cleat may be rectangular in outline.

The cleat A when constructed, whether slightly curved for use on barrels or straight for use on boxes, has what will be in use the 55 vertical body and the flanges E E. The cleat may be applied to a barrel or box by a hammer. Preferably, however, the device is applied by a lever-press of my own invention, which by a single operation and practically 60 without noise forces the points D D into the chime of the barrel or projecting edge of the box and turns over the point C and drives it into the top hoop or stave of the barrel or into corresponding position in a box. The 65 flanges E rest on the barrel or box head just above the croze in a barrel and fit more snugly than a single flange would do. The points D D and C are usually sufficient to firmly hold the cleat in place, and when so held the cleat 70 strengthens the package in amazing degree. When removed to open the barrel or package, no projecting nails are left, as is usual where nails are used to hold a wooden cleat or binder in place.

In case of the device of Fig. 6 nails may be driven through the holes K into the chime of the barrel. Even in such case the nails will be drawn by the removal of the metallic cleat A.

In some instances the corners E' of the cleat may be set down into the barrel or box head.

From the foregoing it will be understood that while my holding-cleat may be of some- 85 what different forms the general principles of operation are the same, that the cleat is held to the barrel or package by a projection turned over the end and into the outside thereof and by projections or points on the inside, while the bracing flange or flanges E 90 lie snugly against the head or cover of the package, and as these flanges extend farther than the croze of the barrel they add largely to the strength of the package in resisting pressure tending to force out the head.

For convenience of description the main body of the cleat may be called the "vertical" flange and the flange or flanges E E may be called the "horizontal" flange. The points D or D', which project rearwardly, have their 100

flat faces horizontal, so as to enter the chime of the barrel in a direction substantially parallel with the grain of the stave. Thus the points enter easily.

5. What I claim is—

1. A holding-cleat composed of a single piece of sheet metal, having a substantially vertical body provided with horizontal flanges at each lower corner, a tongue extending from the upper edge of the vertical body, a notch in the lower edge of said body and between the horizontal flanges, and points struck from the body and extending in opposite direction to the flanges, substantially as described.

10. 2. A sheet-metal holding-cleat having a tongue projecting centrally from one edge and having a corresponding notch at the other edge and a bent flange at each side of said notch, and having integral points projecting from its back, substantially as described.

15. 3. A holding-cleat of sheet metal having a

body and flanges extending from one edge of said body, and having a central tongue extending from the other edge of said body, and 25 having points struck from the body with their flat faces vertical, said points projecting in opposite direction from the flanges, substantially as described.

4. The combination with a barrel or package, 30 of a holding-cleat of sheet metal, having its body lying against the chime of the package, a flange against the head of the package, integral points entering the inner face of the chime, and a tongue extending over the 35 end and into the outside of the package, as set forth.

In testimony whereof I affix my signature in presence of two witnesses.

FREDERICK EDWARD HEINIG.
